DETACHABLE HANDLE FOR SAUCEPANS OR THE LIKE

Richard W. Greger, Corning, N.Y., assignor to Corning
Glass Works, Corning, N.Y.

Filed Jan. 29, 1973, Ser. No. 327,774

Term of patent 14 years

Int. Cl. D7—02

U.S. Cl. D7—132

FIG. 1 is a top plan view of a detachable handle for saucepans or the like embodying my new design.

FIG. 2 is a side elevational view, with the opposite side being a mirror image.

FIG. 3 is a bottom plan view.

FIG. 4 is a front elevational view.

FIG. 5 is a rear elevational view.

I claim:

The ornamental design for a detachable handle for saucepans or the like, as shown and described.
